(57) CLAIM

The ornamental design for a lady's hand or shoulder bag, as shown and described.

DESCRIPTION

FIG. 1 is a front view showing our new design;

FIG. 2 is a side view thereof;

FIG. 3 is a top view thereof in an open position;

FIG. 4 is a front three-quarter view thereof;

FIG. 5 is a front three-quarter view thereof with chain; and,

FIG. 6 is a rear view thereof.

The broken lines showing a handbag chain are for the purposes of illustrating environment and form no part of the claimed design.
